PLATE OF AN UPRIGHT PIANO.

No. 16,658.

Patented Apr. 27, 1886.

UNITED STATES PATENT OFFICE.

PAUL GMEHLIN, OF NEW YORK, N. Y.

DESIGN FOR A PLATE OF AN UPRIGHT PIANO.

SPECIFICATION forming part of Design No. 16,658, dated April 27, 1886.

Application filed March 13, 1886. Serial No. 195,181. Term of patent 14 years.

To all whom it may concern:

Be it known that I, PAUL GMEHLIN, of the city, county, and State of New York, have invented a Design for the Plate of an Upright Piano-Forte, of which the following is a complete specification.

The accompanying photograph represents a face view of my new plate.

This invention relates to a new form of configuration of the plate of an upright piano. The said plate A has a straight edge, *a*, along the top. At its right end this line is met at a right angle by a vertical straight line, *b*. The lower end of the line *b* connects by a curved line, *c*, with another vertical straight line, *d*. The lines *b*, *c*, and *d* form the boundary at the right of the plate A. The lower end of the line *d* is met at a right angle by a lower straight line, *e*, which defines the bottom of the plate A. The line *e* connects by a curved line, *f*,

with the straight upright line *g*, that defines the left edge of the plate A. By these lines *a*, *b*, *c*, *d*, *e*, *f*, and *g* the plate receives a peculiar and characteristic outline or form.

The plate is substantially as wide as it is 25 long, as shown.

I claim—

The design for the configuration of the piano-forte plate A, the same being substantially as wide as it is long, and consisting of 30 the straight boundary-lines *a b*, meeting at a right angle curve *d*, boundary-line *c*, straight boundary-lines *d e*, meeting at a right angle curved boundary-line *f* and straight boundary-line *g*, which meets the line *a* at a right 35 angle, substantially as shown.

PAUL GMEHLIN.
